DESIGN FOR A GAME BOARD

Joseph F. Martin, Jr., and Achiel B. Van Hee, Detroit, Mich., said Van Hee assignor to said Martin, Jr.

Application October 2, 1944, Serial No. 115,554

Term of patent 14 years

(Cl. D34—5)

To all whom it may concern:

Be it known that we, Joseph F. Martin, Jr., and Achiel B. Van Hee, both citizens of the United States of America, and both residing at Detroit, in the county of Wayne and State of Michigan, have invented a new, original, and ornamental Design for a Game Board, of which the following is a specification, reference being had therein to the accompanying drawing forming a part thereof, wherein:

Fig. 1 is a top plan view of a game board, showing our new design;

Fig. 2 is an edge elevational view thereof; and
Fig. 3 is a sectional view thereof taken substantially on the line 3—3 of Fig. 1.

We claim:

The ornamental design for a game board, substantially as shown.
